MEANS AND METHOD OF CONNECTING
AND BLENDING CIGARETTESJohn W. Haley, West Hartford, Conn., assignor
of one-fourth to Jan P. Clary, Hartford,
Conn.

Application October 21, 1931. Serial No. 570,217

1 Claim. (Cl. 131—52)

This invention relates to means and method of connecting and blending cigarettes.

The primary object of the invention is to connect cigarettes together, end to end wherein the individual blend of each cigarette is different for the purpose of obtaining a new blend of the cigarette tobacco and also for doubling the length of the cigarette, economy being noted by the fact that one of the cigarettes is entirely consumed, leaving a single butt end to be discarded.

Other objects of the invention refer to the particular type of connectors for the cigarettes that are preferably constructed of the usual cigarette paper that is consumed during the smoking of the joined cigarettes.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a fragmentary side elevational view, partly in section showing one method of connecting cigarettes end to end with the wrapper of one cigarette telescoped within the wrapper of the other cigarette;

Figure 2 is a side elevational view, partly broken away and shown in section showing two cigarettes joined end to end by a connector device;

Figure 3 is an end elevational view of the connector device shown in Figure 2;

Figure 4 is a side elevational view of the connector device, preferably constructed of cigarette paper with a reinforcing bead at each end;

Figure 5 is a side elevational view of the connector device in collapsed form and ready for application to the ends of cigarettes;

Figure 6 is a side elevational view of another form of connector similar to Figure 4, provided with circumferential rows of slots to relieve the same of material;

Figure 7 is a cross-sectional view taken on line 7—7 of Figure 6;

Figure 8 is a fragmentary side elevational view, partly in section showing two cigarettes connected together end to end by a conical connector; and

Figure 9 is a side elevational view of the conical connector shown in Figure 8.

It is an object of this invention to combine two cigarettes of different blends to obtain an aroma to suit the desire of the individual smoker, the cigarettes being joined together end to end and consequently increasing the length of the cig-

arette and by which method one of the cigarettes is entirely consumed during smoking and only a single butt end remains to be discarded and the means for accomplishing the connection of the cigarettes in end to end fashion comprises a connector device that is preferably constructed of cigarette paper to be consumed during the smoking of the cigarette.

The method of connecting cigarettes is illustrated in Figure 1 wherein the cigarettes 10 and 11 respectively of different blends respectively are joined together in end to end relation with one end of the cigarette 11 telescoping within an end of the cigarette 10 as at 12. The smoke of one cigarette passing through the other cigarette in contact with the tobacco contents thereof produces a different aroma that may be varied in accordance with the character of cigarettes so connected. Usually, one cigarette is insufficient to satisfy the desires of a smoker and by connecting two cigarettes together as illustrated in Figure 1, the combined cigarettes produce the desired results and in addition thereto produce an aroma that may be varied as stated.

Instead of telescoping the cigarette ends as illustrated in Figure 1, they may be connected together in end to end abutting relation by a connector device of tubular form and preferably constructed of cigarette paper, the tubular connector 13 having a reinforcing or strengthening bead 14 at each end. The tube 13 is of a collapsible character as illustrated at 13a in Figure 5 and when collapsed as illustrated in said figure, cigarette ends are moved into engagement therewith with the connector extended to assume the position illustrated in Figure 2 enclosing adjacent abutting ends of the cigarettes 10a and 11a. The connector being constructed of cigarette paper, the same is consumed during the smoking of the connected cigarettes, one cigarette being completely consumed while a single butt end of the other cigarette may be discarded.

The form of connector illustrated in Figures 6 and 7 comprises a tubular body portion 15 having reinforcing end beads 16, this form of connector being non-collapsible and provided with circumferential series of slotted openings 17 to relieve the connector of excess material. With a connector of this character, less paper is added to the connected cigarettes and if desired, the connector 15 may be constructed of non-inflammable material and saved for re-use.

In the form of invention illustrated in Figures 8 and 9, the cigarettes 10b and 11b are joined by the conical connector 18 having a reinforcing 110

bead 19 at its larger end. The smaller end of the conical connector 18 is telescoped within one end of the cigarette 10b as illustrated in Figure 8 and one end of the cigarette 11b is telescoped within the larger end of the conical connector, the cigarettes being so connected that the tobacco contents thereof merge into one another as illustrated.

From the above detailed description of the invention, it is believed that the method of accomplishing the blending of aromas will at once be apparent as well as the means for accomplishing the same and while there are herein shown and described the preferred embodiments of the in-

vention, it is nevertheless to be understood that minor changes may be made therein without departing from the spirit and scope of the invention as claimed.

I claim:—

A connector for a pair of aligned cigarettes comprising a paper tube of uniform diameter from end to end and having an imperforate central zone and a reinforcing rib at each end, said tube having in each part between the central zone and ribs a series of circumferentially spaced longitudinal slots.
